STITCHING MACHINE

Bradley Fuller, Newburyport, and Edward H. Winslow, Danvers, Mass., assignors to United Shoe Machinery Corporation, Flemington, N. J., a corporation of New Jersey

Application June 17, 1953, Serial No. 25,534

Term of patent 14 years

(Cl. D55—1)

To all whom it may concern:

Be it known that we, Bradley Fuller and Edward H. Winslow, citizens of the United States, residing at Newburyport and Danvers, respectively, both in the county of Essex and Commonwealth of Massachusetts, have invented a new, original, and ornamental Design for a Stitching Machine, of which the following is a specification, reference being had to the accompanying drawings, forming part hereof.

In the drawings,

Fig. 1 is a view in front elevation of a stitching machine embodying our new design;

Fig. 2 is a view in right side elevation of the machine shown in Fig. 1;

Fig. 3 is a perspective view on a somewhat larger scale looking at the left side and the rear of the machine; and

Fig. 4 is a plan view of the machine.

We claim:

The ornamental design for a stitching machine, substantially as shown.
